ICE-PICK SHEATH

Jesse L. Hart, Los Angeles, Calif.

Application April 21, 1931. Serial No. 531,843

2 Claims. (Cl. 224—2)

The present invention comprehends the provision of a sheath of novel construction, primarily intended for use in conjunction with an ice-pick, and designed to frictionally hold the tool against casual separation from the sheath.

Another and important object of the invention resides in the provision of a sheath having a passage in its lower end communicating with the interior of the same, to permit water to drain therefrom and also allow for the circulation of air through the sheath to maintain the latter in a dry condition.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

Figure 1 is a front elevation of the invention.
Figure 2 is a side elevation thereof.

Figure 3 is a sectional view on line 3—3 of Figure 1.

Figure 4 is a sectional view on line 4—4 of Figure 1.

Figure 5 is a sectional view on line 5—5 of Figure 1.

Figure 6 is a front elevation of a modified form of the invention.

Figure 7 is a side elevation of the device shown in Figure 6.

Figure 8 is a vertical section on line 8—8 of Figure 6.

Figure 9 is a horizontal section on line 9—9 of Figure 6; and

Figure 10 is a horizontal section on line 10—10 of Figure 6.

The sheath forming the subject matter of the present invention comprises a backing member 10 which is preferably constructed from a single length or piece of leather, and which may vary in size and configuration without departing from the inventive idea. The backing member 10 is slotted as at 11 adjacent its upper end to accommodate itself to a belt or the like 12 upon which it is supported. Arranged on one side of the backing member 10 is a pocket, which

is also preferably constructed from a single piece of leather, and which pocket has its marginal edges 13 stitched or otherwise suitably secured to the backing member as at 14. These marginal edges are also riveted to the backing member at their upper ends as at 15. The pocket in its

entirety may of course vary in size and cross sectional contour without departing from the invention, but is essentially of a contour similar to the shape of the tool adapted to be received thereby, so that the walls of the pocket will frictionally engage and effectively hold the tool within the pocket, and against casual separation therefrom. As hereinabove stated, the sheath is primarily intended for use in connection with an ice-pick including a shank 16 and a handle 17, so that the pocket is formed with a relatively large upper portion 18 to receive and engage the handle 17, and a relatively narrow restricted portion 19 which effectively engages the shank 16 of the tool as shown in Figure 5. This narrow portion 19 of the pocket of course merges into the upper enlarged portion 18, as the pocket is formed from a single piece of material, the lower edge of which terminates flush with the lower edge of the backing member 10. The pocket is open at both ends, to permit water to drain from the lower end of the pocket, and to also permit the circulation of air therethrough in a manner to be presently described.

The entire structure is substantially reinforced at its lower end by a U-shaped reinforcing member, which may be constructed from any suitable material, preferably metal. This member which is indicated at 20 receives the lower end of the sheath, and is riveted as at 21 to both the pocket and the backing member 10, the rivets being arranged at opposite sides of the reduced or restricted portion 19 of the pocket as illustrated. The reinforcing member 20 is substantially of the same width as the lower end of the sheath, while the closed end of this reinforcing element is spaced a slight distance from the lower edge of the sheath to provide a transverse passage 22, which communicates with the pocket to permit the water to drain therefrom through the passage 22. Obviously, the passage 22 opens at the opposite sides of the sheath, which allows for the circulation of air through the sheath, with a view of quickly drying the interior of the latter, maintaining the sheath in a reasonably dry condition and thus prevent damage to the material from which the article is constructed.

In the construction of Figures 6 to 10 inclusive, the reinforcing member 20 has its rear portion arranged against the front face of the back member 10 and provided with an extension 23 which extends to a point above the top of the pocket member where it is passed rear-

wardly through a slot 24 in the back member and clinched and riveted as at 25 against the back of the latter. In this way, the back member is stiffened and effectively protected against damage by engagement of the point of the ice pick therewith as the latter is repeatedly inserted in the sheath. Otherwise, the construction of both forms of the invention is substantially the same and similar reference characters 10 are used to indicate like parts throughout the several views.

While it is believed that from the foregoing description the nature and advantages of the invention will be readily understood, I desire 15 to have it known that I do not limit myself to what is herein illustrated and described, and that such changes may be resorted to when desired as fall within the scope of what is claimed.

20 What I claim as new is:

1. A sheath for ice picks comprising a stiff substantially flat leather back member, a pocket member embodying a longitudinally folded piece of flexible leather having its marginal edges secured against the front face of the back member to form a tapered pocket open at both ends and adapted to snugly receive and frictionally engage the blade and handle of the ice pick to retain the latter in the sheath, and an elongated

80 U-shaped metal reinforcing member secured on the lower end of the sheath with its intermediate portion slightly spaced below the lower end of the pocket member to form a drainage passage and having its front portion shaped at its longitudinal center to conform to the lower end of the pocket.

85 2. A sheath for ice picks comprising a stiff substantially flat leather back member, a pocket member embodying a longitudinally folded piece of flexible leather having its marginal edges secured against the front face of the back member to form a tapered pocket open at both ends and adapted to snugly receive and frictionally engage the blade and handle of the ice pick to retain the latter in the sheath, and an elongated 90 U-shaped metal reinforcing member secured on the lower end of the sheath with its intermediate portion slightly spaced below the lower end of the pocket member to form a drainage passage and having its front portion shaped at its longitudinal center to conform to the lower end of the pocket, the rear portion of said reinforcing member being arranged against the front face of the back member and provided 95 with an extension which extends along the rear of the pocket to a point above the top of the pocket member.
